UNITED STATES PATENT OFFICE

GEORGE EDWARDZ BJÖRKMAN, OF DJURSHOLM, SWEDEN

DESIGN FOR A CONTROL FOR HAIR WAVING APPARATUS

Application filed March 30, 1932. Serial No. 43,335. Term of patent 14 years.

To all whom it may concern:

Be it known that I, GEORGE EDWARDZ BJÖRKMAN, a subject of the Kingdom of Sweden, and a resident of Djursholm, Sweden, whose post-office address is 114 East 16th Street, New York city, New York, have invented a new, original, and ornamental Design for Control for Hair Waving Apparatus, of which the following is a specification, reference being had to the accompanying drawing, forming part thereof, in which—

Figure 1 is a plan view of the hair waving apparatus.

Figure 2 is an end elevation of the hair waving apparatus.

Figure 3 is a front elevation of the hair waving apparatus.

I claim:

The ornamental design for a control for hair waving apparatus, as shown.

GEORGE EDWARDZ BJÖRKMAN.
